(57) **CLAIM**

The ornamental design for rack for screw capped tube, as shown and described.

DESCRIPTION

FIG. 1 is a front elevational view of a rack for screw capped tube incorporating the design of our new invention;

FIG. 2 is a left-side elevational view thereof;

FIG. 3 is a right-side elevational view thereof;

FIG. 4 is a rear elevational view thereof;

FIG. 5 is a top plan view thereof;

FIG. 6 is a bottom plan view thereof;

FIG. 7 is a cross-sectional view thereof taken along line 7—7 of FIG. 5; and,

FIG. 8 is a cross-sectional view thereof taken along line 8—8 of FIG. 5.

The features of the rack for screw capped tube shown in phantom lines are not elements of the design of our new invention.
